CONTROL DEVICE FOR A PROTECTIVE
ALARM SYSTEMHerbert S. Shoffstall, 428 Keswick Ave., Glenside, Pa.
Filed Dec. 26, 1963, Ser. No. 333,344
8 Claims. (Cl. 200—61.62)

This invention relates to a control device for a protective alarm system.

The alarm control device of the present invention is suitable for home, office or other installation. It is designed to be operated by the opening or movement of a window, door, or other closure element to trigger an alarm system. The alarm system itself is not part of the present invention. The alarm system may include any of a large variety of electrically operated alarm devices, such as bells, horns, sirens, lights, etc., and may also include a master control panel.

The principal object of the present invention is to provide an alarm control device.

A further object is to provide an alarm control device which may be installed on or at a window, door or other closure element, to be actuated by the opening or movement thereof to trigger an alarm system of some kind.

While the alarm control device of the present invention is adapted for a large variety of installations and purposes, it will be convenient to illustrate and describe the device installed at a well-known type of double-hung wood window.

In the drawing:

FIG. 1 is a perspective illustration of a wood window frame and double-hung window sash showing the alarm control device of the present invention installed therewith;

Fig. 2 is a front elevational view of the alarm control device of FIG. 1;

FIG. 3 is the top plan view, partly in section, looking down along the line III—III of FIG. 2;

FIG. 4 is a side elevational view, partly in section, looking in along the line IV—IV of FIG. 2;

FIG. 5 is a front perspective view of the installed alarm control device;

FIG. 6 is an exploded view in perspective showing the component parts of the alarm control device as seen from the rear;

FIG. 7 is a front perspective view of the channel block, one of the component parts shown in FIG. 6;

FIG. 8 is a rear elevational view, partly in section, looking in along the line VIII—VIII of FIG. 4, showing the control mechanism in the OFF position;

FIGS. 9—12 are views similar to FIG. 8 showing the control mechanism in the ON, actuated, reset-ready and reset positions, respectively, and

FIG. 13 is a schematic illustration of one form of alarm system controllable by the control device of the present invention.

It will be convenient to refer first to the exploded view of FIG. 6. In FIG. 6, the component parts 21, 22, 24, 26, 28, 31, 32, 33 and 34, when assembled, are mounted on the movable window sash and form what may be conveniently identified herein as the sash-mounted control device 40. The device 40 is illustrated in FIG. 1 as mounted in the upper left corner of the lower window sash 41.

Referring again to FIG. 6, the reference number 50 identifies an elongated channel member of electrically non-conductive material which, in FIG. 1, is shown to be mounted vertically on the inside of the window frame 52 along the upper half of the frame. Inside of the channel 50, two strips 53 and 54 of copper or other suitable conductive material are mounted in parallel spaced-apart relation. The strips 53 and 54 may preferably be T-shaped

2

and inserted in grooves provided in the channel member 50, as indicated in FIG. 6.

The remaining components of FIG. 6, identified as 61, 62, 63 and 64, when assembled, form what may be conveniently identified herein as the sliding block 60. This block 60 is inserted into the channel member 50 and is interlocked to the sash control device 40 by one means or another, as will be described. Thus, as the lower window sash 41 is moved up or down, the block 60 follows, sliding along in channel member 50.

Channel member 50 may preferably be formed of hard plastic material. It is open on one side, the side which faces inwardly toward the window sash. Flanges 55 and 56, one on each side of the opening, extend from the channel member 50 toward the window sash. The cavity of channel member 50 is thus T-shaped in cross-section. Into this cavity, the T-shaped block 61 is inserted. The narrow portion of block 61 is provided with a cross-slot 69. The wide portion of block 61 is provided with a cross-slot 65 at about the mid-section. This latter slot 65 receives the rectangular bar 64.

Bar 64 is made of brass or other suitable conductive material. It is provided with a tapped hole at its center for receiving the threaded stem of plunger 62. Thus, bar 64 functions as the nut for attaching the plunger 62 to the block 61.

Plunger 62 has a head portion 67 and a stem portion 68 the end of which is threaded.

The narrow portion of the T-shaped block 61 is provided with a horizontally disposed cylindrical hole 66 for receiving the stem and head of the plunger 62. As seen best in FIG. 7, hole 66 is located at the level of the cross-slot 65.

A helical compression spring 63 is placed in the hole 66 and functions to bias or load plunger 62 so that its head 67 tends to protrude beyond the outer surface of the leg of the block 61, as seen in FIGS. 8—12. When the block assembly 60 is placed in the channel member 50, the spring-biased plunger 62 maintains the rectangular nut 64 in contact with the conductive strips 53, 54. If, by any means, the plunger 62 is depressed, the nut 64 is moved back out of contact with the strips 53, 54. The function of the window sash control device 40 is to control the position of the plunger 62, thereby to control whether the conductive nut 64 does or does not connect together electrically the strips 53 and 54.

Referring again to FIG. 6, the sash-mounted control device 40 consists of a pair of rectangular bodies 21 and 22 which may preferably be of aluminum. These bodies 21 and 22 are mounted in face-to-face relation on the window sash 41, as by four screws, as illustrated in FIGS. 1, 2, 3 and 5. The face of block 22 is provided with a horizontally disposed upper slot 23 for receiving the toothed bar or rack 24, and with a horizontally disposed lower slot 25 for receiving the toothed bar or rack 26. Between the upper and lower slots 23 and 25, the face of block 22 is provided with a generally circular well 27 for receiving the gear or pinion 28. The block 22 is provided with a center hole 30 for receiving the shaft 29 of the pinion 28.

A control knob 31 is adapted to be placed on the protruding end of the pinion shaft 29 and to be secured thereto, as by the set screw 32.

The face of the block 22 is also provided, at one side thereof, with a vertically elongated recess 37a which, when the two blocks 22 and 21 are in face-to-face abutting relation, mates with a recess 37b in the face of block 21. Each of the recesses 37a and 37b has an upper portion which is shallow in depth and a lower portion which is deeper. When the two blocks 22 and 21 abut each other, the recesses 37a and 37b form a cylindrical upper recess

37c of shallow depth having a diameter slightly larger than that of the head 67 of plunger 62, and an adjoining cylindrical lower recess 37d having substantially the same diameter as 37c but of greater depth. As seen in FIGS. 8-12, the shallow-depth recess 37c receives plunger 62 but is not deep enough to allow the loaded plunger to move sufficiently far to bring nut 64 into contact with the strips 53, 54 at the wall of channel member 50. However, the deeper recess 37d, when it receives plunger 62, is deep enough to allow contact between nut 64 and strips 53, 54 to be made.

The rear surface of block 22 is provided with an off-center hole, not visible in FIG. 6 but seen in section in FIG. 3, for receiving the spring 33 and the ball detent 34. The inner surface of control knob 31 is provided with three circular recesses on an arcuate path for receiving the ball detent 34. These recesses identify the OFF, ON and RESET positions, as indicated in FIG. 6 of the drawing. Control knob 31 is also provided with an indexing pointer 35.

In assembling the sash-mounted control device 40, the control knob 31 is placed on the pinion shaft 29 in such angular position that when the pointer 35 points to the OFF position (FIG. 2) the ball detent 34 is in the OFF recess (FIG. 6) and the racks 24 and 26 occupy the positions illustrated in FIG. 8. When the knob 31 is rotated (clockwise in FIG. 2; counterclockwise as viewed from the rear in FIG. 6) until the ball detent 34 enters the ON recess (FIG. 6), the racks 24 and 26 are changed from the positions shown in FIG. 8 to the positions illustrated in FIGS. 9 and 10. Further rotation of the knob 31, until the ball detent 34 enters the RESET recess (FIG. 6), will change the racks 24 and 26 to the positions illustrated in FIGS. 11 and 12.

The operation of the alarm control device, as used in a typical manner, may best be described by referring to FIGS. 8-12. These figures view the device from the rear.

In the OFF position, FIG. 8, the protruding end of the upper rack 24 enters the cross slot 69 in the leg of block 61 and locks the sash-mounted control device 40 to the block assembly 60, and the two move up and down together as the window sash 41 is moved up and down. In this interlocked position, the plunger 62 is in alignment with the upper shallow recess 37c and the head 67 of the plunger is spring-pressed by spring 68 into this recess 37c. The conductive bar or nut 64 is rearward of the copper strips 53, 54 and not in contact therewith.

Assume that the window is in a bedroom and that the occupant desires to retire for the night with the window partly open for ventilation. The lower window sash 41 is raised to the desired height carrying the sliding block assembly 60 upward with the sash-mounted control box 40. The control knob 31 is then turned to the ON position. This places the upper and lower racks 24 and 26 in the positions illustrated in FIGS. 9 and 10 in which the end of rack 24 no longer extends into the cross-slot 69 of the sliding block assembly 60. The plunger head 67 is still in the shallow upper recess 37c and the conductive nut 64 is still in the position illustrated in FIGS. 8 and 9, out of contact with the conductive strips 53 and 54.

Assume that an intruder, in an attempt to enter the room, starts to raise the lower sash 41. As soon as the sash 41 is moved upward, in the direction indicated by the arrow in FIG. 10, the sash-mounted control box 40 moves upward relative to the block assembly 60 and the head 67 of the plunger slips down into the lower recess 37d. This recess 37c, being deeper, allows the spring-biased plunger to move outwardly and the conductive nut 64 is pulled forwardly and makes immediate contact with the conductive strips 53 and 54. These strips are connected to the electrical alarm system, and as soon as the electrical circuit is closed, by the nut 64 connecting the strips 53, 54, the alarm is actuated. The nut 64 is maintained in contact with the strips 53, 54, so long as the

plunger head 67 is in the deep lower recess 37d. As seen in FIG. 10, as soon as the plunger slips into the deep lower recess 37d, the plunger interlocks the block assembly 60 to the sash-mounted control box 40, and the window sash 41 may thereafter be moved in either the up or down direction without disturbing the interlocked condition and without breaking the contact of nut 64 with the strips 53, 54. Thus, the alarm system remains energized.

To reset the alarm control device, the control knob 31 is turned to the RESET position (clockwise in FIG. 1; counterclockwise in FIGS. 8-12). In so doing, the lower rack 26 is pushed outwardly against the end of the plunger head 67 and pushes the plunger 62 back into the recess 66 in the block assembly 60 until the end of the plunger head 67 is substantially in alignment with the end of the shallow recess 37c. The conductive nut 64 is now pushed away from the copper strips 53 and 54, as seen in FIG. 11. The window sash 41 is then lowered, in the direction of the arrow in FIG. 12 and almost immediately the head 67 of the plunger slips into the shallow upper recess 37c, as depicted in FIG. 12. The upper rack 24 is now in alignment with the cross slot 69, and the knob 31 is then turned to the OFF position in which the upper rack 24 is in the fully extended interlocking position illustrated in FIG. 8. Or, knob 31 may be turned ON.

The connecting together of the conductive strips 53 and 54 by the conductive nut 64 closes an electrical circuit of an alarm system which may take any one of many forms. FIG. 13 represents schematically one form of alarm control circuitry.

In FIG. 13, reference numeral 70 represents an alarm device of some kind, such as a bell, or a horn, or a lamp, or any other suitable electrical device. Device 70 is adapted to be energized by a 110-volt supply 71 through a relay switch 72. Relay switch 72 is normally maintained open by a low 6-volt supply supplied from transformer 73 through suitable conductor leads including the conductive window strips 53 and 54. Transformer 73 is supplied from the usual 110-volt house supply. When the plunger 62 slips into the deep recess 37d and allows the nut 64 to contact the strips 53 and 54, relay 72 is shorted out, and the relay switch closes, thereby connecting the 110-volt source 71 to the alarm device and actuating it.

It will be seen that in a system such as that of FIG. 13, only a low voltage is supplied to the window strips 53 and 54. Thus, there is no danger of electrical shock or fire.

The overall alarm system may, of course, be as elaborate, as desired. A master control panel may, for example, be used at a selected location to indicate the particular window or door which has been moved in a direction to open the same.

While the preferred embodiment of this invention has been described in some detail, it will be obvious to one skilled in the art that various modifications may be made without departing from the invention as hereinafter claimed:

Having thus described my invention, I claim:

1. In a protective system for a window, door, or other movable closure element; a two-part control device having a first part installed on said movable closure element and a second part installed adjacent thereto; said second part comprising a pair of paralleled conductive strips at spaced separation mounted adjacent to said movable closure element, a plunger, a conductive bar connected to said plunger and transversely disposed relative to said conductive strips, and a biasing spring for biasing said plunger in a direction to move said conductive bar into contact with both said strips; said first part comprising a body mounted on said movable closure element, a recess in said body having a shallow portion and a parallel adjacent deep portion, each portion of said recess being adapted separately to receive said plunger, said deep portion having

a depth sufficient to allow said biased plunger to move in the biased direction sufficiently to move said conductive bar into contact position with said strips, said shallow portion having an insufficient depth to allow said biased plunger to move said conductive bar to contacting position, interlocking means for interlocking said first and second parts together in such position that said plunger is aligned with said shallow portion of said recess, and manual control means for controlling said interlocking means.

2. A control device according to claim 1 characterized in that said second part includes an elongated channel member of non-conductive material in which said conductive strips are mounted at spaced separation.

3. A control device according to claim 2 further characterized in that said second part includes a block of non-conductive material slideable within said channel member, and further characterized in that said plunger, conductive bar and biasing spring are carried by said slideable block.

4. A control device according to claim 3 further characterized in that said interlocking means comprises a rack and pinion mounted in said body of first part, and a slot in said slideable block for receiving the end of said rack when moved forward by said pinion.

5. A control device according to claim 4 further characterized in the provision of a second rack mounted in the body of said first part and disposed in alignment with the deep portion of said recess, said second rack being adapted to be moved forward by rotation of said pinion into said deep portion of said recess, for moving said biased plunger against the action of its biasing spring to reset said control device.

6. A control device according to claim 5 further characterized in that said pinion is mounted on a shaft which

protrudes from the body of said first part, and in that a control knob is secured to the protruding end of said pinion shaft.

7. A control device according to claim 6 further characterized in that the control knob is provided with detent means for placing said control knob in any one of three positions corresponding to the off, on and reset conditions of said control device.

8. In a protective alarm system for a movable closure element; a first body mounted on said movable closure element; a second body disposed adjacent to said first body and having a cavity therein for receiving a plunger; a plunger in said cavity; a compression spring in said cavity tending to cause said plunger to protrude forwardly from said cavity; a bar of electrically conductive material connected to the rearward end of said plunger; electrical conductor means fixedly mounted near to said bar; means for normally aligning said first and second bodies in relative positions such that said first body prevents said plunger from being moved fully forward by said spring for preventing said conductive bar from making contact with said fixed electrical conductor means; recess in said first body for receiving said plunger, said recess being normally out of alignment with said plunger but movable 20 into alignment therewith upon movement of said closure element, thereby to allow said spring to move said plunger into said recess, thereby to move said conductive bar into contact with said fixed electrical conductor means.
